Primary Examiner — Bridget L Eland(74) *Attorney, Agent, or Firm* — Nicholson De Vos Webster & Elliott LLP(57) **CLAIM**

The ornamental design for a gateway router, as shown and described.

DESCRIPTION

FIG. 1 is a front perspective view of a gateway router showing our new design;

FIG. 2 is a front elevation view of the gateway router of FIG. 1;

FIG. 3 is a rear elevation view of the gateway router of FIG. 1;

FIG. 4 is a right view of the gateway router of FIG. 1;

FIG. 5 is a left view of the gateway router of FIG. 1;

FIG. 6 is a top view of the gateway router of FIG. 1;

FIG. 7 is a bottom view of the gateway router of FIG. 1; and, FIG. 8 is a bottom perspective view of the gateway router of FIG. 1.

The broken lines in the figures illustrate portions of the gateway router that form no part of the claimed design.
